(57) **CLAIM**

The ornamental design for a holder for box lid or the like, as shown and described.

DESCRIPTION

FIG. 1 is a perspective view of the holder for box lid or the like in an assembled state, showing my design;

FIG. 2 is a front view thereof;

FIG. 3 is a rear view thereof;

FIG. 4 is a left-side view thereof;

FIG. 5 is right-side view thereof;

FIG. 6 is a top view thereof;

FIG. 7 is a bottom view thereof; and,

FIG. 8 is a front view thereof in a disassembled state.

The dot-dash-dot broken lines depict the boundaries of the claim and form no part thereof. The dash-dash broken lines depict portions of the holder for box lid or the like that form no part of the claimed design.

The jagged break lines surrounding the vertical slots in the two support elements of the holder for box lid or the like in FIG. 8 indicate that no portion of the article beyond what is shown forms part of the claimed design.
